DESIGN FOR A PENDANT

Sam Jacobson, New York, N. Y., assignor to Executive Jewelers Purchasing Corp., a corporation of New York

Application January 26, 1946, Serial No. 125,986

Term of patent 3½ years

(Cl. D45—15)

To all whom it may concern:

Be it known that I, Sam Jacobson, a citizen of the United States of America and a resident of the city of New York, in the county of New York and State of New York, have invented a new, original, and ornamental Design for a Pendant, of which the following is a specification, reference being had to the accompanying drawing, forming a part thereof.

Fig. 1 is a front view of the pendant showing my design.

Fig. 2 is a side view thereof.

Fig. 3 is a top plan view thereof.

I claim:

The ornamental design for a pendant, substantially as shown.

SAM JACOBSON.
